FIG. 1

FIG. 2.

INVENTOR.

BY Samuel T. Shore
Judah B. Feisskin, attorney

UNITED STATES PATENT OFFICE

106,640

DESIGN FOR A DRESS OR SIMILAR ARTICLE

Samuel Ted Shore, New York, N. Y.

Application September 3, 1937, Serial No. 71,448

Term of patent 3½ years

To all whom it may concern:

Be it known that Samuel Ted Shore, a citizen of the United States and resident of New York city, in the county of New York, State of New York, has invented a new, original, and ornamental Design for a Dress or Similar Article, of which the following is a specification, reference being had to the accompanying drawing, forming part thereof, and in which,

Fig. 1 is a front view of a dress, embodying my new design; and

Fig. 2 is a rear view of the same.

I claim:—

The ornamental design for a dress or similar article substantially as shown.

SAMUEL TED SHORE.
